[57] CLAIM

The ornamental design for a plastic hook for use to releasably attach opposite ends of an elastic cord, as shown and described.

DESCRIPTION

FIGS. 1 and 2 are respectively top and bottom plan views of a plastic hook for use to releasably attach opposite ends of an elastic cord and to show my new design;

FIG. 3 and 4 are respectively left and right side elevational views thereof;

FIGS. 5 and 6 are respectively rear and front elevational views thereof; and,

FIG. 7 is a perspective view thereof.
